UNITED STATES PATENT OFFICE.

JESSE J. YEATES, OF MONTGOMERY, ALABAMA, ASSIGNOR OF ONE-HALF
TO CHARLES MILTON SMITH, OF MONTGOMERY, ALABAMA.

NON-REFILLABLE BOTTLE.

No. 807,229.

Specification of Letters Patent.

Patented Dec. 12, 1905.

Application filed March 30, 1905. Serial No. 252,936.

To all whom it may concern:

Be it known that I, JESSE J. YEATES, a citizen of the United States, residing at Montgomery, in the county of Montgomery and State of Alabama, have invented new and useful Improvements in Non-Refillable Bottles, of which the following is a specification.

This invention relates to certain new and useful improvements in non-refillable bottles of the type employing a ball-valve for closing the aperture in the throat of the bottle, and has for its object to provide a device which shall be simple and reliable in operation and economical to manufacture.

In order that the invention may be clearly understood, I have illustrated the same in the accompanying drawing, in which the figure is a view in sectional elevation of a bottle constructed according to my invention.

Referring to the drawing, 1 indicates the bottle proper, which is provided with a neck 2, the throat 3 of which is conical in outline—that is to say, in the normal position of the bottle the throat diverges outwardly from the bottom to the top of the neck. The neck 2 is continued into a chamber 4, in the top 5 of which is secured a tube 6, which projects a suitable distance above the top 5 and within the chamber 4, as shown. Said tube has an open outer end 7 for receiving the ordinary cork and a closed lower end 8, located within the chamber 4. Near its bottom end the tube 6 is provided on two opposite sides with apertures 9. Said tube is also provided around its sides adjacent to the top 5 with openings 10.

11 indicates a ball-valve which is adapted to fit snugly within the throat 3 of the neck, so as to close said throat and prevent liquid being poured into the bottle 1.

In operation and before the ball-valve 11 is inserted the bottle 1 is filled with the desired fluid and then the ball-valve 11 is placed in the tube 6 and the bottle tipped to one side, so that said ball-valve will fall out of one or the other of the openings 9 and seat in the throat 3. The space between the wall of the tube 6 and the wall of the chamber 4 is sufficient to allow the ball-valve 11 to pass between them, so that when it is desired to pour out the contents of the bottle when the

latter is turned up the said ball-valve will roll down into the chamber 4 and remain there, while the liquid flows out through the openings 9 or 10. When the bottle is placed in an upright position, the ball-valve will again fall into the throat 3 and close the same. The openings 10 permit all the fluid to be drained from the bottle. In practice the neck 2 is of a length sufficient to prevent the ball-valve from being displaced by shaking the bottle—say, about three times as long as the diameter of the ball 11. The bottom 8 of the tube prevents the removal of the ball 11, which cannot be taken out of the chamber 4 without breaking the neck 2.

All the parts of the device are constructed of glass.

Having thus fully described my invention, what I claim as new, and desire to secure by Letters Patent, is—

1. A non - refillable bottle, comprising a bottle proper provided with a neck having an inclined or conoidal throat, a chamber extending above said neck and forming a continuation thereof, a tube located in the top wall of said chamber and projecting within the latter, said tube being provided at its bottom with an aperture, and a ball-valve adapted to seat in the throat of said bottle and of a size to pass through said aperture.

2. A non - refillable bottle comprising a bottle proper having a neck provided with an inclined or conoidal throat, a chamber located above said neck formed as a continuation thereof, a tube located in the top wall of said chamber and projecting within the latter, said tube having an open upper end and a closed lower end and provided within the chamber adjacent to the top wall thereof with an opening and at its lower end portion with a circular aperture, and a ball-valve adapted to seat in the throat of said neck and of a diameter to pass through said aperture.

In testimony whereof I have hereunto set my hand in presence of two subscribing witnesses.

JESSE J. YEATES.
